BREATHING APPARATUS

Joseph B. Dym, Pittsburgh, Pa., assignor to Mine Safety Appliances Company, Pittsburgh, Pa., a corporation of Pennsylvania

Application October 8, 1934, Serial No. 747,275

5 Claims. (Cl. 128—191)

This invention relates to breathing apparatus, more particularly to portable self-contained oxygen breathing, or inhalation, apparatus, such as, for example, the type used by firemen, in mine 5 rescue work, and for similar purposes.

Apparatus of the type contemplated herein embodies means for recirculating and regenerating air in a closed cycle to maintain it fit for breathing. Customarily it includes a regenerator through which respiration air is passed for the removal of carbon dioxide, a cooler for reducing the temperature of the respiration and regenerated air, means for introducing into the treated air a certain amount of oxygen to supply that consumed in respiration, and a mouthpiece through which the regenerated air is inhaled and exhaled into and from the associated regenerating apparatus. The mouthpiece is provided with an outlet connection to the regenerator for removal 10 of exhaled air, and an inlet connection for introduction of regenerated air freed from carbon dioxide and admixed with supplemental oxygen.

The present invention applies particularly to improvements in the mouth piece and affiliated 20 elements of such apparatus.

As previously constructed, the inhalation and exhalation tubes leading to and from the mouthpiece have been rigidly connected in fixed position to opposite sides of the mouthpiece. Because of such rigid construction the weight of 30 the tubes has exerted a lever action upon the mouthpiece, causing a relatively severe pressure to be applied to the face or chin of the wearer, thus increasing the normal discomfort attendant upon artificial breathing means.

Such apparatus, to be efficient, must include means to avoid mixing of the regenerated air and the respiration air. To this end the mouthpieces are commonly provided with a pair of flow-controlling valves. One of these valves is intended to open upon inhalation to permit regenerated air to enter the mouthpiece, the other valve, leading to the exhalation tube, being simultaneously closed by the negative pressure created 40 within the mouthpiece in the act of inhalation. Upon respiration the positive pressure within the mouthpiece closes the inhalation valve and opens the exhalation valve. Extended experience has shown that the valve constructions 45 previously proposed for this purpose have been not completely satisfactory.

Commonly these mouthpiece valves have been positioned either horizontally or substantially vertically. In the use of horizontal valves the 50 weight of the valve members must be overcome in

the act of breathing, and while the added breathing resistance is small, it may increase the normal breathing effort sufficiently to decrease the efficiency of the wearer, particularly when the apparatus is worn over long periods of time or during 5 periods of severe exertion. The vertical type valve does not close by gravity, and it has been found that if the user breathes lightly the valves may not be wholly closed, which may be dangerous. The disadvantages of incomplete valve closure are known to those familiar with the art. On the other hand, if the user of such a mouthpiece breathes heavily enough to insure positive closing of the valves, the mouthpiece becomes 10 subject to the disadvantages of those embodying 15 horizontal valves due to the added resistance to breathing.

It is among the objects of this invention to provide an improved mouthpiece which avoids the strain heretofore caused by the inhalation and 20 exhalation tubes, provides positive action inhalation and exhalation valves which require a minimum of breathing effort and are positively closed irrespective of the breathing force applied to them.

A further object is to provide an improved 25 nose clip for use with breathing apparatus mouthpieces, which is adjustable to the needs of the wearer.

The invention may be described in connection 30 with the accompanying drawing in which Fig. 1 represents a front view, partly in section, of the preferred embodiment; and Fig. 2 a front view of the preferred embodiment of the nose clip.

In accordance with the invention the inhalation and exhalation tubes are rotatably connected to the inhalation and exhalation openings, respectively, of the mouthpiece, whereby when the mouthpiece is in use the tubes may be individually rotated upon, or relative to, the 40 mouthpiece to adjust their angle to relieve strain and thus to afford the most comfortable position for the wearer.

With reference to the valve construction embodied in the invention, the mouthpiece is provided with a pair of gravity actuated valves associated one with the inhalation opening, and another with the exhalation opening, these valves being inclined at an angle such that the valves close positively under the action of gravity, but 50 such that in the act of breathing it is unnecessary to overcome the entire weight of the movable valve members. Most suitably the valves are inclined at an angle approximately 45° to the horizontal. 55

Having reference now to the drawing, Fig. 1 shows a mouth piece of conventional form including a casing member 1 having at opposed ends an inlet opening 2 and an outlet opening 3. The mouthpiece is divided into three chambers by a pair of inclined diaphragm members 4 and 5 which are perforated to provide flow openings 6 and 7, respectively. On the upper side of the diaphragms are mounted cages 8, for example of the form conventionally used in breathing apparatus mouthpieces, for limiting the upward movement of flap valve members 10 and 11.

These diaphragms thus divide the mouthpiece into an inlet chamber 12, an outlet chamber 13 and an intermediate chamber 14 which is provided with a forwardly projecting mouth tube 15 of a conventional form.

In the act of inhalation the negative pressure in chamber 14 causes valve 10 to open to permit 20 regenerated air to be drawn into chamber 14 from inhalation tube 16 through chamber 12. Simultaneously, the negative pressure in the chamber 14 closes valve 11, cutting chamber 13 off from chamber 14. When the wearer exhales there is 25 created a positive pressure in chamber 14 which closes valve 10 and opens valve 11, thus establishing communication between chambers 13 and 14 to permit the respired air to pass into outlet chamber 13 and thence to the regenerator, not 30 shown, through exhalation tube 17.

In accordance with the invention diaphragms 4 and 5 are mounted at an angle such that the valves close positively through the action of gravity, but substantially away from the horizontal so 35 that it is unnecessary in the breathing act to overcome the entire weight of the valves in causing them to open. With such a construction gravity usually will suffice to completely close the valves, but should they not do so, the acute angle 40 at which they are mounted suffices to cause them to close tightly upon the application of very slight pressure, as in light breathing. In the embodiment shown these diaphragms are mounted at an angle of approximately 45°, which has been found 45 to involve a minimum of breathing resistance while affording maximum safety to the wearer.

An important aspect of the invention resides in the manner of associating the inhalation and exhalation tubes 16 and 17 with the inlet and outlet 50 openings 2 and 3, respectively. In accordance with the invention these tubes are rotatably associated with the corresponding openings in the mouthpiece. In the embodiment shown the inhalation tube 16 and the exhalation tube 17 are 55 provided integrally with fittings 18, Fig. 1, adapted to snugly but rotatably engage openings 2 and 3, respectively, as shown in the drawing. Advantageously the ends of the mouthpiece forming openings 2 and 3 are provided with outwardly 60 extending flanges 19 to insure retention of the tubes thereon. This permits the wearer to adjust the angle of each tube relative to the mouthpiece and independently of each other, to relieve the strain heretofore encountered with mouth- 65 pieces having the tubes rigidly connected to them, as will be understood by those familiar with the use of such apparatus. By thus adjusting these elements maximum comfort is afforded in relation to the mouthpiece.

70 An additional advantage is that with this construction it becomes possible to shorten the overall length of the mouthpiece, thus decreasing the weight of the apparatus, which is advantageous, and affording less interference with the field of vision of the wearer.

It will be understood that tubes 16 and 17 are associated with any suitable form of regenerating apparatus, the construction of which is well known to those skilled in the art and constitutes no part of the present invention.

5 Fittings 18 may be of such resiliency as thereby and in cooperation with flanges 19 to insure retention of the tubes on the mouthpiece. Or, for added safety, various additional means known to the art, such as hose clamps, may be used. In 10 the drawing the tubes are shown as being wrapped to the mouthpiece by wires 20 positioned to act just inside flanges 19. This causes the tubes to be held securely on the mouthpiece openings while permitting swivelling movement of the 15 fittings on the mouthpiece. Preferably the wires 20 are covered by adhesive tape 20a.

The mouthpiece is shown as provided with straps adapted to be passed about the head of the wearer for fastening the mouthpiece in position.

Although in the preferred embodiment fittings 18 are integrally formed with tubes 16 and 17, it will be understood that this is not essential to the invention, it being possible to connect separately formed fittings to the tubes by means available in the art.

Breathing apparatus of this type may be provided with a nose clip for the purpose of rendering it easier to breathe through the mouth without inhaling or exhaling air through the nose. As previously constructed, such clips have been of substantially constant and unadjustable tension, and for this reason disadvantages have been encountered in the use of such clips. For instance, 35 the tension of a clip may be satisfactory for one person and entirely unsatisfactory for others, either because it is insufficient to completely close the nasal passages, or because it is so severe as to cause substantial discomfort.

A further feature of the invention resides in a 40 nose clip adapted efficiently to prevent respiration through the nose together with maximum comfort to all persons. In this aspect of the invention the nose clip is constructed to permit adjustment of the tension of the nostril-engaging members. The preferred embodiment is 45 shown in Fig. 2. A pair of nostril-engaging members 21, of soft rubber, for example, adapted to be applied to opposite sides of the nose for applying pressure thereto to close the nasal passages are individually connected as shown, to bowed springs 22. The extended ends of the springs are overlapped for a substantial distance and engaged slidably by a sleeve member 23. Sleeve member 23 thus holds the springs together 50 to maintain members 21 in position and likewise permits the ends of springs 22 to be moved inwardly or outwardly and thereby to adjust the spring tension applied to the nostrils through 55 members 21. In this manner the wearer can 60 adjust the tension of the springs to suit his nostril.

The nose clip may be attached to the apparatus, to prevent its loss, in any suitable manner, as by attaching it to a strap 24 associated with the head harness shown in Fig. 1.

According to the provisions of the patent statutes, I have explained the principle and construction of my invention and have illustrated and described what I now consider to represent its 70 best embodiment. However, I desire to have it understood that, within the scope of the appended claims, the invention may be practiced otherwise than as specifically illustrated and described.

I claim:

1. In a breathing apparatus, a mouthpiece provided with inhalation and exhalation openings disposed laterally of the mouthpiece, an inhalation tube, an exhalation tube, and swivel connections between said inhalation tube and inhalation opening and between said exhalation tube and exhalation opening.
2. In a breathing apparatus, a mouthpiece provided with inhalation and exhalation openings, an inhalation tube rotatably associated with said inhalation opening, an exhalation tube rotatably associated with said exhalation opening, a pair of oppositely acting valves associated one with each of said openings and controlling admission of fluid to and expulsion of fluid from the mouth-piece, and said valves being associated with the mouth-piece at an acute angle to its longitudinal axis and thereby providing positive gravity closure and minimized resistance to breathing created by the valves.
3. In a breathing apparatus, a mouth-piece provided with inhalation and exhalation openings, an inhalation tube rotatably associated with said inhalation opening, an exhalation valve rotatably associated with said exhalation opening, a pair of oppositely acting valves associated one

with each of said openings and controlling admission of fluid to and expulsion of fluid from the mouth-piece, and said valves being associated with the mouth-piece at an angle of substantially 45 degrees to its longitudinal axis and thereby providing positive gravity closure and minimized resistance to breathing created by the valves.

4. In a breathing apparatus, a nose clip comprising a pair of opposed nostril-compressing members each having a bowed spring connected at one end thereto, said spring urging said members towards each other, the extended ends of said springs being overlapped, and a sleeve slidably engaging said overlapped spring portions and thereby permitting adjustment of the pressure exerted by said springs on the nostrils through said members.

5. In a breathing apparatus, a mouth-piece provided with laterally positioned, axially aligned inhalation and exhalation openings disposed at opposite ends of the mouth-piece, an inhalation tube, an exhalation tube, and swivel connections between said inhalation tube and inhalation opening and between said exhalation tube and exhalation opening.
